UNITED STATES PATENT OFFICE.

WILLIAM H. DOANE, OF CINCINNATI, OHIO, ASSIGNOR TO J. A. FAY & CO., OF SAME PLACE.

DESIGN FOR A BAND-SAW FRAME.

Specification forming part of Design No. 5,268, dated September 19, 1871.

To all whom it may concern:

Be it known that I, WILLIAM H. DOANE, of Cincinnati, in the county of Hamilton and State of Ohio, have invented and produced a new and original Design for a Band-Saw Frame, of which the following is a specification:

The nature of my design is fully represented in the accompanying photographic illustration, to which reference is made.

The part whose design or configuration is claimed to be new and original is the frame A,

which supports the operative parts of the machine.

I claim as my invention—

The design for a band-saw frame, as shown. In testimony of which invention I hereunto set my hand.

W. H. DOANE.
